UNITED STATES PATENT OFFICE.

JOSEPH WIESER, OF ST. JOHNSVILLE, NEW YORK.

DUPLEX TRACKER-BAR FOR PNEUMATIC MUSICAL INSTRUMENTS.

No. 917,825.

Specification of Letters Patent.

Patented April 13, 1909.

Application filed January 20, 1909. Serial No. 473,285.

To all whom it may concern:

Be it known that I, JOSEPH WIESER, a citizen of the United States, residing at St. Johnsville, Montgomery county, State of New York, have invented new and useful Improvements in Duplex Tracker-Bars for Pneumatic Musical Instruments, of which the following is a specification.

The standard tune sheets adapted to operate with the tracker bars of pneumatic musical instruments are of different compass and are generally provided with either 65 or 88 longitudinal rows of perforations, so as to actuate either 65 or 88 piano hammers. The perforations of both kinds of tune sheets, however, occupy the same width, so that in tune sheets adapted to actuate 65 hammers, the perforations are comparatively wider than in those adapted to actuate 88 hammers.

In order to permit the use of both kinds of tune sheets on one and the same piano or piano player, I provide a tracker bar which has two parallel rows of air openings, one row containing 65 openings, while the other row contains 88 openings. The openings of either one row are adapted to be coupled to the music producing means, the connection being such that when one row communicates with said means, the other row is cut off therefrom. For this purpose a perforated slide is employed which controls the openings and is within reach of the person operating the piano, so that the instrument may be readily adapted to the use of tune sheets having a different compass.

In the accompanying drawings: Figure 1 is a front view of part of a piano case provided with my improved duplex tracker bar; Fig. 2 a vertical section on line 2—2, Fig. 1; Fig. 3 a side view of the slide operating means; Fig. 4 a front view of the channel block, with the slide and cover partly broken away; Fig. 5 a front view of the slide; Fig. 6 a plan, partly in-section, of the channel block and cooperating parts; Fig. 7 an enlarged vertical cross section on line 7—7, Fig. 6; Fig. 8 a horizontal section on line 8—8, Fig. 7; and Fig. 9 a vertical section on line 9—9, Fig. 7, with the air tubes omitted.

The numeral 10 indicates the upper front board of a piano case having an oblong opening 11 which is adapted to be closed by a sliding door 12. Back of opening 11 there is mounted in the piano case a box 13 con-

tinuing a fixed duplex tracker bar 14 and adapted to receive a perforated music sheet A. This sheet passes from a delivery roller 15 across tracker bar 14, to a receiving roller 16, to which rotary motion is imparted by a suitable motor, (not shown). Tracker bar 14 has an upper row of openings 17 and a lower row of openings 18, both rows being of the same length, but row 17 comprising a larger number of openings than row 18. Back of tracker bar 14 there is secured to box 13, a channel block 19 provided with a series of parallel U-shaped ducts or channels 20, the number of which corresponds to the number of openings in row 17. If this row contains 88 openings, which is the preferred number, block 19 has an equal number of ducts 20. The front board 21 of block 19 is provided with a pair of parallel longitudinal grooves 22, 23 adapted, respectively, for the reception of the members 24, 25 of a slide B. The reduced board-section or partition 26, intermediate upper groove 22 and the upper legs of ducts 20, is provided with a series of perforations 27, each perforation opening into one of said ducts 20. It is preferred to arrange perforations 27 in oblique rows, each containing three of said perforations. The reduced board-section 29, intermediate lower groove 23 and the lower legs of ducts 20, is provided with a series of similarly arranged perforations 30, each perforation communicating with one of said ducts 20. The perforations 27, 30 are so arranged and spaced that the lower perforations of the lower partition are in true vertical alinement with the lower perforations of the upper partition. In like manner, the central and upper perforations of the lower partition are, respectively, in vertical alinement with the corresponding perforations of the upper partition, (Fig. 4).

Upper slide-member 24 is provided with perforations 31 which, in number and arrangement, correspond exactly to those of partition 26. Lower slide member 25 has perforations 32 which similarly correspond to those of partition 29. Perforations 32, however, stagger or are out of vertical alinement with the corresponding perforations 31, so that when a vertical line is drawn through any perforation of the upper slide-member, (Fig. 5), said line will pass through a solid imperforate portion of the lower slide-member, and vice versa.

Slide-members 24, 25 are confined within their respective grooves by a cover 33, which is secured to front board 21 by screws 34, or otherwise. Cover 33 is provided with an upper set of perforations 35 and a lower set of perforations 36. Perforations 35 are equal in number to perforations 27 and are axially alined with such perforations. In like manner, perforations 36 equal in number and arrangement those of perforations 30, with which they are alined. If desired, perforated linings or gaskets 37 may be interposed between partitions 26, 29 and slide-members 24, 25, respectively, and also between said members and cover 33. Perforations 35 communicate by tubes 38 with upper openings 17 of tracker bar 14, while perforations 36 communicate by tubes 39 with the lower openings 18 of said tracker bar. A pair of diverging shields 40, extending from the tracker bar toward the back 41 of box 13, conceal these tubes from view, impart a neat appearance to the interior of the box and guard the tubes against injury.

Each of the U-shaped channels 20 is by a tube 42 connected to the bellows that actuate the tune producing means, (not shown). Slide-members 24, 25 are connected at one end by a cross bar 43 to which is fulcrumed a link 44 pivoted to the rear arm 45 of a shaft 46 which is journaled in bearings 47 of box 13. The front crank 48 of shaft 46 is provided with a knob or button 49 that constitutes a handle. If arm 48 is moved downward into the position shown in Fig. 1, slide B, is, through arm 45 and link 44, shifted toward the right, so that perforations 31 will register with perforations 27, 35 or partition 26 and cover 33. In this position of slide B, the perforations 32 of lower slide-member 25 are out of alinement with perforations 30 and 36 of partition 29 and cover 33, so that perforations 30 are closed against the atmospheric air. In this way tracker bar openings 17 will communicate through tubes 38, perforations 35, 31, 27, channels 29 and tubes 42, with the tune producing means, while the openings 18 of the tracker bar are out of communication with such means. When a tune sheet having a compass of 88 notes is fed across the tracker bar, the corresponding music will be produced. If it is desired to set the tracker bar for a tune sheet having a range of 65 notes only, knob 49 is swung upward until it covers a fixed index 50. In this position, perforations 32 of slide-member 25 register with perforations 30 and 36 of partition 29 and cover 33, so that communication is established between tracker bar openings 18 and the tune producing means through tubes 39, perforations 36, 32, 30, channels 20 and tubes 42, while the openings 17 of the tracker bar are closed against communication with channels 20

The device is thus set ready for use in connection with a tune sheet having a compass of but 65 notes.

If desired, index 50 may be provided with the number 88, as shown in Fig. 1. When this number is exposed, it indicates that the tracker bar is set for use in conjunction with tune sheets having a range of 88 notes, while when the number is concealed by knob 49, the tracker bar is set for tune sheets having a compass of 65 notes.

It will be seen that by my invention, tune sheets prepared for different ranges of piano harmonies may be used in one and the same instrument having but a single tracker bar. In this way all standard tune sheets obtainable in the market may be utilized for operating an instrument, without in any way changing the construction of the latter.

I claim:

1. A duplex tracker bar provided with two parallel rows of openings, combined with a box having air channels, means for connecting the perforations of either one row with said channels, and means for simultaneously disconnecting the openings of the other row from said channels.

2. A duplex tracker bar provided with two parallel rows of openings, combined with a box having air channels, and a perforated slide adapted to connect the openings of either one row with said channels.

3. A duplex tracker bar provided with two parallel rows of openings, combined with a box having air channels, and a perforated slide adapted to connect the openings of either one row with said channels and simultaneously disconnect the openings of the other row from said channels.

4. A duplex tracker bar provided with an upper opening and a lower opening, combined with a box having an air channel, a slide having an upper perforation and a lower perforation, either perforation being adapted to communicate with the air channel, and means for connecting the upper and lower slide perforations, respectively, with the upper and lower tracker bar openings.

5. A duplex tracker bar provided with an upper opening and a lower opening, combined with a box having an air channel, a cover having an upper perforation and a lower perforation, a perforated slide adapted to establish communication between either perforation and the air channel, and means for connecting the upper and lower cover perforations, respectively, with the upper and lower tracker bar openings.

6. A duplex tracker bar provided with an upper opening and a lower opening, combined with a grooved box having an air channel, a perforated slide engaging the box groove, a perforated cover engaging the slide, and means for connecting the cover perforations with the tracker bar openings.

7. A duplex tracker bar provided with two rows of openings having different ranges, combined with a box having a series of air channels, a first perforated slide-member channels, a first perforated slide-member 5 interposed between said channels and one of said rows, a second perforated slide-member interposed between said channels and the other row, the perforations of the first slide-member being arranged in a staggering relation to those of the second slide-member, and means for simultaneously actuating both slide-members.
8. A duplex tracker bar provided with two parallel rows of openings, combined with a box having air channels, a perforated slide 10 adapted to connect the openings of either one row with the air channels, and means for operating the slide.
9. A duplex tracker bar provided with two parallel rows of openings, combined with a 15
- 20
- box having air channels, a perforated slide having air channels, a perforated slide adapted to connect the openings of either one row with the air channels, an arm connected to the slide, and means for operating said arm.
10. A duplex tracker bar provided with two parallel rows of openings, combined with a box having air channels, a perforated slide 25 adapted to connect the openings of either one row with the air channels, an arm linked to the slide, a button connected to the arm, and an index adapted to be covered by the button.

Signed by me at St. Johnsville, New York,
this 16th day of January, 1909.

JOSEPH WIESER.
